COLLAPSIBLE CONTAINER AND DISPENSING HOLDER THEREFOR

Alfred A. Moore, 5602 N. Burton, San Gabriel, Calif.

Filed Apr. 29, 1957, Ser. No. 655,563

15 Claims. (Cl. 222—105)

This invention relates to collapsible containers and more particularly to an improved container of this type designed for use with a simple and effective dispensing holder, and to a new method of charging collapsible containers.

It has been common practice for many years to package fluent materials of various types in collapsible tubular containers. It is desirable that the fluent contents be dispensed under controlled conditions and in such manner that the issuing stream can be used in the manner and quantities required for the purposes at hand. While it is possible to dispense the contents from such containers by hand, this is unsatisfactory, inconvenient, and uneconomical for many purposes. Mechanically operated dispensing holders have been devised for use with containers filled with caulking compounds, putty and the like fluent materials. Although such holders have served a useful purpose they have many shortcomings and disadvantages which it is the purpose of this invention to overcome. In general the devices referred to are bulky, heavy and difficult to manipulate. A particular disadvantage to the small home users of fluent material packaged in flexible containers is the high cost of dispensing holders of the types heretofore provided, their cost exceeding that of the fluent material container by several times.

The present invention avoids the shortcoming referred to above and others by providing a specially designed, inexpensive, collapsible container and a simple one-piece holder having a dispensing nozzle at one end. The two-piece assembly is adapted to be held in the user's hand and is so formed that the user's fingers are effective to collapse the container and dispense the contents precisely as required for the work at hand. The tip end of the container, when severed, provides a discharge opening positioned to register with the nozzle part of the holder with the result that the contents can be dispensed directly into a crevice or other irregularity to be filled as the dispensing holder is manipulated advantageously to direct the material into the crevice.

Another feature of the invention is a specially designed thin-walled collapsible container formed entirely in one piece and purchased sealed full of fluent material ready for application. Preferably made of plastic, the container is sealed most simply by pressing its opposite walls against one another and heat sealing them together by passage of a heated iron or between heated rollers in accordance with known sealing techniques. Any desired number of separate units can be charged and sealed along a given length of the tubular material following which the units are severed from one another along the wide seams between charges. If the seams are formed at an angle to the axis of the tubes, as is contemplated by the present invention, the resulting container is appropriately shaped to fit snugly within the nozzle of the onepiece holder also forming a feature of the invention.

Accordingly it is a primary object of this invention to provide an improved dispensing container and a co-

2

operating holder useful in dispensing the content thereof under conveniently controlled conditions.

Another object of the invention is the provision of an improved collapsible container sealed filled with fluent contents in such manner that the severing of an end portion thereof provides a convenient dispensing opening.

Another object of the invention is the provision of a simple one-piece dispensing holder adapted to be held in the user's hand with a portion of a collapsible container 10 assembled thereto exposed for the application of dispensing pressure from the clenching action.

Another object of the invention is the provision of a simple and inexpensive container charged with prepared crevice filling material ready for distribution into crevices through a restricted opening formed by severing the tip end of the container.

Another object of the invention is the provision of an improved method for making sealed collapsible containers charged with fluent material.

20 These and other more specific objects will appear upon reading the following specification and claims and upon considering in connection therewith the attached drawing to which they relate.

25 Referring now to the drawing in which a preferred embodiment of the invention is illustrated:

Figure 1 is an exploded perspective view of a holder for collapsible containers and of the specially designed container adapted for use therewith;

Figure 2 is a longitudinal sectional view through the 30 holder and including a dot-and-dash line showing of the position occupied by a collapsible container when properly assembled thereto; and

Figure 3 is a side elevational view of a series of connected collapsible containers before separation into separate charged units.

Referring to Figures 1 and 2, there is shown a dispensing device designated generally 10 for use with collapsible containers formed from thin rigid material such as sheet metal but preferably from molded plastic material.

Holder 10 has a main body 11 crescent shaped in cross-section and having a diameter conveniently grasped in the hand of a user. Viewed from one aspect, main body 11 might be described as tubular with the upper half cut away along a combination straight and curved contour line indicated at 12. One end of the main body has formed integral therewith a dispensing nozzle 13 of the general configuration illustrated and provided at its pointed forward end with a small discharge port 14. While as herein shown this port is generally circular, it will be understood

45 that it may have various shapes depending on the material being dispensed and the nature of the crevice or surface to which the material is being dispensed. For example, it may be desired to dispense a thin ribbon of material in which case port 14 will have a narrow broad opening corresponding to the width and thickness of ribbon desired

50 to be dispensed with the wider axis of the discharge port 14 suitably disposed for the application of the discharging ribbon of fluent material.

The dispensing device 10 also features integral means 60 positioned to project into the side of a collapsible container as pressure is applied to its contents, such indentation being effective to resist rearward movement of the container out of nozzle 13. One preferred method of accomplishing this end comprises a hood 15 overlying the rear end of nozzle 13 in the manner illustrated in Figures 1 and 2 with lip 16 spaced sufficiently close to the underlying walls of the holder body as to indent the side wall of the container.

65 It will therefore be evident that as pressure is applied to a collapsible container supported in the holder the fluent contents will expand the end of the tube against the interior walls of nozzle 13 locking the container in such manner that the small dispensing open-

70

ing 18 in registry with nozzle port 14 is held in tight sealing engagement therewith.

While the described hood 15 and lip 16 provide a convenient and effective arrangement for locking the collapsible container releasably sealed within nozzle 13 it will be understood that other arrangements are equally effective. For example, the dispensing holder may be formed with ridges or ribs 19 projecting upwardly from its inner wall and extending transversely of its longitudinal axis. Two transverse ribs 19 of this character are illustrated in Figure 2 and may be used alone or in combination with hood 15 and its lip 16 to hold container assembled in the dispensing device.

A further important feature of the invention is a collapsible tubular container designated generally 20 and preferably formed from thin pliable material such as one of the many plastic materials now available, a vinyl plastic being found particularly suitable. This material is preferably formed into an endless, seamless tube of a diameter corresponding to that of the main body of the dispensing holder. The method provided by this invention providing sealed containers from long tubes of this material includes sealing one end of the tube in any well known manner, a particularly convenient and effective method comprising the application of heat transversely across collapsed wall portions of the tube to effect fusing of the contacting walls together without adversely affecting the strength or thickness of the tube wall. Paste or fluent material is then charged into the opposite open end of the tube to fill a section thereof adjacent its closed end. At this point the course of procedure is optional when filling the tube with certain fluent materials but not optional when filling with others. Thus if the fluent material is of a type which does not cling tenaciously to the interior walls of the tubing, the contents may be pinched off as the tube walls are pressed together following which an effective heat-fused seam 21 may be provided across the tube in known manner. When filling with other materials this procedure is not feasible because the material clings to the tube side wall. In this case it is necessary to fill a section of the tubing and then seal off the tubing immediately above the top of the contents before filling the next higher section. In this latter instance filling is accomplished by alternately filling and sealing a section before filling the next section.

A particular feature of the filling operation of the tubing to provide containers usable with the dispensing device illustrated in Figures 1 and 2 comprises forming the transverse seals 21 at a sharp angle to the longitudinal axis of the tube, the inclination corresponding generally with the inclination of the end wall of dispensing nozzle 13. This seam is made sufficiently broad to permit severing of the seam along the median line 22 to provide separate sealed containers 23, the severing being performed with a sharp knife, scissors or the like.

Once the containers have been severed from the main body of the tubing the pointed ends 25 are found to incline naturally downwardly away from the main body of the tube in a manner conforming with the contour of nozzle 13 as shown in Figure 2. Initially and before severing along lines 22 corners 26 opposite corners 25 are inclined outwardly also. However, once the containers are severed from the long tube, corners 26 tend to disappear leaving corners 25 inclined away from the body of the tube.

Although the collapsible container may be filled with any fluent material which it is desired to dispense, one material contemplated for use with the present invention comprises a prepared crack-filling compound prepared from gypsum powder and an oil-based vehicle which dries quickly upon exposure to the open air. This material, or any other suitable fluent material, may be dispensed from the sealed containers using the holder 10 by severing the tip 18 from one of the pointed ends 25 of the container and then assembling it within dispensing holder 10 in the manner illustrated in Figure 2.

The dispensing and spreading of the material is conveniently performed by holding the device in the hand and applying the slight pressure to exposed portions of the container necessary to dispense the contents at a desired rate as nozzle port 14 is maneuvered over the area or crevice to be filled with the discharging fluent material. If the controlling pressure is applied from the rear end of the container forwardly towards nozzle 13, as it conveniently may be, the forward portion of the dispensing device remains fully inflated for more convenient handling. Furthermore the unused contents are confined to the forward end of the container. If the entire contents are not required, the container can be removed from the dispensing device and the container folded back upon itself to seal the discharge port 18 until ready for use.

It is pointed out in particular that during the dispensing operation the pressure applied to the contents acts to expand the forward end of the container walls outwardly against hood 15 and about the inwardly projecting holding ribs 19-19, with the result that the forward end of the container remains fully inflated against the walls of the nozzle. For this reason the contents cannot creep between the walls of the container and those of nozzle 13. Nor is it possible for the container to become displaced from the dispensing holder. It is also pointed out that the nozzle tip of the holder 10 may be formed in various contours and that it may lie below, above or flush with the lower surface of the main body 11 as found most suitable for a particular use of the dispenser.

While the particular dispensing device and method of making collapsible containers for use therewith herein shown and disclosed in detail is fully capable of attaining the objects and providing the advantages hereinbefore stated, it is to be understood that it is merely illustrative of the presently preferred embodiments of the invention and that no limitations are intended to the details of construction or design herein shown other than as defined in the appended claims.

I claim:

1. A dispensing device for use in dispensing a stream of fluent plastic material from a collapsible container mounted therein and for distributing the dispensed stream, said device comprising a trough-like holder of relatively rigid thin material open along one side and shaped at one end to conform substantially with the end of a collapsible tubular container sealed at the end thereof at an angle to the longitudinal axis and to provide a converging nozzle having a small discharge opening at its tip to receive the container contents from the foremost tip end of the container, said device being adapted to support a collapsible container charged with plastic material to be dispensed with the discharge end of the container pressed against the inner wall of said nozzle adjacent the dispensing tip thereof, said device further being adapted to be grasped within the hand with the user's fingers positioned to apply pressure through the open side thereof to dispense plastic material as desired.

2. A dispensing device as defined in claim 1 wherein the end of said holder opposite said nozzle end is open to facilitate the insertion and removal of collapsible containers and facilitating the application of dispensing pressure from the rear end of a container supported within said holder.

3. A dispensing device as defined in claim 1 wherein the larger end of said converging dispensing nozzle is provided with means projecting inwardly from the edge thereof toward the opposite side of the nozzle and effective to engage the discharge end of a dispensing container to hold the same releasably assembled within said nozzle.

4. A dispensing device as defined in claim 1 wherein said dispensing nozzle is inclined downwardly away from the bottom of said trough-like holder at a convenient angle for directing discharging plastic into a crevice or against a surface to be coated therewith.

5. A dispensing device as defined in claim 1 formed of molded plastic material.

6. A dispensing device as defined in claim 1 including inwardly projecting means on the interior wall of said device adapted to indent a collapsible container crosswise thereof as pressure is applied to dispense its contents and effective in holding a container against displacement from said nozzle.

7. A dispensing device for use in dispensing and distributing the fluent contents of an elongated collapsible container, said device comprising a one-piece elongated hollow holder of generally crescent shape in cross section and adapted to be grasped within the hand for the application of pressure against a collapsible tubular container supported therewithin, said holder having a converging dispensing nozzle at one end the axis of which lies at a substantial angle to the axis of said holder and which is adapted to enclose and support the end of a collapsible container with its discharge opening pressed in sealing registry with the similarly shaped walls adjacent the discharge opening of said nozzle.

8. A dispensing device for use in dispensing and distributing the fluent contents of an elongated collapsible container, said device comprising a one-piece elongated hollow holder of crescent shape in cross section adapted to be grasped within the hand for the application of pressure against a collapsible tubular container supported therewithin, said holder having a converging dispensing nozzle projecting from one rim edge of said holder at one end thereof and adapted to enclose and support the end of a collapsible container with its discharge opening pressed in sealing registry with the discharge opening of said nozzle, and means integral with said holder positioned to engage said container and to hold the discharge end thereof against displacement from said nozzle as dispensing pressure is applied to said container.

9. In the combination with a hand-grasped dispensing holder of the type having an open-sided tubular body constricted at one end to provide a dispensing nozzle with its axis inclined to the axis of said tubular body, that improvement which comprises a readily detachable collapsible dispensing container sealed full of fluent material and insertable into said holder with the severed tip end thereof pressed against and in alignment with a dispensing nozzle formed in the end of said holder, said container comprising a thin walled tubular body of flexible plastic material sealed closed at one end along a seam inclined to the axis of the container and otherwise free of reinforcing adapted to have its sharp tip end severed to provide a discharge opening positioned to register with the nozzle opening of a dispensing holder.

10. A dispensing device for use in filling cracks and the like with a suitable fluent filler, said device comprising a one-piece rigid holder adapted to fit snugly against one side and about one end of a collapsible tubular container having its dispensing end terminating on the bias, one end of said holder being formed with a dispensing nozzle shaped to seat snugly the bias cut end of a collapsible container with the small tip end of the nozzle located at the foremost rim edge of said holder in position to receive and seat the foremost tip end of the bias cut collapsible container.

11. A dispensing device as defined in claim 10 characterized in that said holder includes means on the side thereof disposed opposite said dispensing nozzle for receiving and engaging over the portion of the bias cut of a tubular container to hold the same within said dispensing tip thereof pressed against the interior walls of said dispensing nozzle during application of pressure to the rearward portion of the container.

12. A dispensing device for use in dispensing the contents of a collapsible container from one end corner

thereof, said device comprising an elongated rigid member shaped to fit within the hand and open along one side to receive a collapsible container of the type adapted to dispense from one end corner thereof, one end of said device being closed except for a dispensing nozzle in one rim edge, said closed end including means opposite said dispensing nozzle adapted to engage snugly over the adjacent end portion of a collapsible container and hold the dispensing opening of the container pressing against the interior walls of said dispensing nozzle when pressure is applied to the side walls of the container.

13. A dispensing device for use with collapsible containers, said device being formed to fit over one end of a collapsible container to dispense the contents thereof through a dispensing nozzle fitting snugly over a nozzle-like protuberance formed off center from the longitudinal axis of the container with the axis of the dispensing nozzle disposed at an angle to the axis of the container, and means at the dispensing end of said device adapted to interlock with the dispensing end of a collapsible container as pressure is applied to rearward portions thereof to hold the container assembled to said device with its nozzle-like protuberance seated snugly within said dispensing nozzle notwithstanding the application of pressure to the container.

14. A collapsible container sealed closed with a charge of fluent material adapted to take a set when exposed to air, said container being adapted to be inserted in a hand-grasped dispensing holder and to be squeezed to dispense the fluid contents thereof into a cavity desired to be closed, said container comprising an elongated tubular body of flexible plastic material charged with fluent material which takes a set when exposed to air, said tubular container being sealed closed at its ends, one end of said container being sealed closed along a seam extending transversely thereof and inclined to the longitudinal axis of the container to provide a closed pointed tip end adapted to be converted into a dispensing nozzle for said fluent material when the tip thereof is cut away, the axis of said dispensing nozzle being inclined away from the axis of the body of the container and being formed entirely by said flexible plastic material and the end closure seam of the container.

15. A combined container and dispenser for fluent material, said container having an elongated tubular body of a size suitable for grasping and holding in the palm of the user's hand and being formed of thin-walled impervious plastic material capable of being heat fused together and immune to attack by the container contents, said body being closed at one end and charged with fluent material, the walls of said body at the other end thereof being heat fused together along a seam inclined away from the longitudinal axis of the container to form a pointed end adapted to provide a dispensing nozzle for the container contents when the tip of said pointed end is cut away, the size of the dispensing opening being dependent on the length of the tip which is cut away, and the axis of said dispensing nozzle lying at an acute angle to the axis of said tubular body.
